HELICOPTER TOY

Nancy B. Ruczynski, Grand Rapids, Mich.

Application March 10, 1949, Serial No. 80,624

1 Claim. (Cl. 46—75)

1

This invention is associated with toys designed around the principles of flying machines generally known as "helicopters." In this type of machine, the weight of the toy is supported in the air by the action of lifting forces generated by a rotating propeller operating in a substantially horizontal plane. It is the custom to provide lateral forces causing the movement of the toy in a direction parallel to the ground by causing the lifting propeller, or "rotor," to assume a slight tilt with respect to the horizon. A component of the total resultant of force contributed by the rotor is thus disposed in a horizontal direction, and creates the desired lateral or forward-moving force. The gyroscopic action due to the rotating blades is generally sufficient to give a considerable stability to the angle of the rotor with respect to the horizon. Coupled with this effect the weather-vane tendency on the part of the body of such a toy will cause the body to align itself with the direction of movement established by the angle of tilt. In this manner the flight attitude of such a toy is seen to be established for any given set of conditions. It may also be noted that it is the usual custom to impart rotational energy to the rotor system by the use of a twisted wire engaging a non-circular aperture in a disk which is in driving relationship with the rotor. As the wire is pulled through this aperture, rotation is imparted at a sufficiently high velocity to cause the lifting action noted above. The inertia of the rotor which has been once brought up to speed will be sufficient to continue the rotation for a long enough period against the drag forces of the air to assure that the toy remains in flight for a considerable length of time.

The present invention is particularly concerned with that portion of such a toy as is described above which relates to the support of the rotor upon the body of the toy. In view of the relatively fragile nature of such a toy when assembled, it is considered very desirable to provide a rotor bearing system which not only has the necessary operating characteristics, but is capable of being disassembled so that the components of the device may be packaged in a container of practical size. The bearing action which is involved in the present invention has two aspects, namely: (a) the bearing action involved at the time the twisted wire is being forcibly pulled through the driving system, and (b) the bearing action occurring when the device is in flight and supported by the aerodynamic forces operating upon the lifting rotor.

The present invention further provides a bear-

ing system which will permit a considerable angle of tilt of the axis or rotation of the rotor with respect to the axis of the rotor-supporting system. The action of the law of gravity will generally cause the center of gravity of the body of the device to be disposed upon a line directly below the center of the rotor bearing. There will be a tendency to assume this position regardless of the particular angle of tilt of the revolving rotor with respect to the horizon. If such a bearing does not provide for this angle of tilt, the gyroscopic forces operating upon the rotor and the aligning effect of the law of gravity upon the mass of the body of the toy will conflict to form a binding action in the bearing which will considerably increase the resistance to rotation thereof and dissipate the rotating energy of the propeller in friction. The obvious results of this characteristic is the failure of the toy to maintain flight for any considerable length of time, and also to cause the body of the device to be rotated in response to the friction noted above. If this frictional engagement at the bearing is considerable, the "weather-vane" tendency of the body will not be sufficient to maintain a relatively fixed direction of the body with respect to the tilt of the rotor.

The preferred form of the present invention comprises a substantially vertical post which is detachably mounted on the body of the toy, this post being provided with a journal and bearing portion adjacent its upper end. The journal portion of the device is adapted to cooperate with the central opening of the rotor and maintain the lateral alignment of the rotor with respect to the body of the toy. In addition to this lateral bearing relationship, the preferred form of this invention provides a thrust bearing relationship for supporting the weight of the toy during the flight thereof. A second thrust-bearing system is provided for counteracting the thrust generated by the user of the toy as the twisted wire is pulled through the driving system. Preferably the two thrust-bearing surfaces are provided by opposite sides of a metallic flange disposed substantially transversely to the axis of the supporting post. The journal section noted above is preferably disposed directly below this flange, so that as the toy comes to flight position the propeller or rotor tends to climb up the journal section until the under side of the flange terminates such upward movement and forms the thrust-bearing through which the lift forces are transmitted.

The driving means utilized in the present in-

vention comprises a simple clip in the preferred form, the central portion of which has a non-circular aperture for engagement with the twisted wire inserted through the center of the supporting column. The surface which contains this non-circular aperture is preferably formed in a curvature which cooperates with a similar curvature of the above noted flange in order to secure the alignment of the axis of rotation of the clip with the axis of the supporting column. A series of engaging legs is disposed to reach around the outer diameter of the bearing flange and to engage suitable portions of the rotor to drive the same. Preferably the supporting column is of such a diameter as to permit the passage of the central opening of the rotor along its entire length with the exception of the diameter of the lifting flange. With this arrangement, the rotor may be said to be confined between the said flange and the retaining action of the engaging legs of the driving clip. When the device is at rest in the vertical position, the weight of the rotor is transferred through the engaging legs to the top side of the bearing flange which cooperates with the under surface of the central area of the driving clip. As the twisted wire is pulled through the column to generate the rotational speed of the rotor, the pressure of engagement between the upper or top part of the flange and the under side of the driving clip is considerably increased, but as soon as the wire is pulled through the orifice the aerodynamic forces operating upon the rotor will cause the rotor to move to contact the under side of the flange and thereby lift the toy from the starting position on top of the manually-retained spool through which the conventional twisted wire is pulled.

The features of the present invention will be further analyzed by a discussion of the particular embodiment which is illustrated in the accompanying drawings. In these drawings:

Figure 1 is an elevation of a completely assembled helicopter toy embodying the present invention, with the rotor and bearing system shown in sections.

Figure 2 is a perspective view of the driving clip utilized in Figure 1.

Figure 3 is an enlarged view of the thrust flange of the central column, and the center section of the rotor and the driving clip shown in a position taken by these components while the toy is in flight.

Figure 4 shows the components of Figure 3 with the maximum amount of tilt permitted by this particular bearing system which permits the rotor to be slanted to contribute a lateral, or forward-moving force.

Referring to Figure 1, the assembly is shown in the starting position with the twisted wire 10 and the holding spool 11 in position to be grasped by the user. The toy itself essentially comprises the body portion 12, which is provided with the column-engaging elements 13 and 14. Directly to the left or rear of the column-engaging elements, the body portion 12 is provided with the tail-boom 15 and the vertical stabilizer 16. For the sake of appearance, imitation windows are formed in the body portion 12 as indicated at 17, 18 and 19.

The central column assembly 20 is received as shown within the engaging elements 13 and 14 with sufficient grip to retain the weight of the body portion 12 so that the device may remain in an assembled position during flight. It may be noted that the force generated by pulling the

twisted wire downwardly through the column to begin the rotation of the propeller passes through the column 20 and is transmitted through the engagement of the column with the holding spool.

As the twisted wire 10 is pulled in the starting process, it cooperates with the non-circular opening 21 in the driving clip 22. The opening 21 causes the driving clip to be rotated through engagement with the spiral of the wire, and this rotation is imparted to the lifting rotor through the engagement of the legs 23 with the central portion of the rotor as shown. In addition to the torque contributed by the twisted wire to the driving clip 22, a considerable down-load is applied to the clip which must be transmitted through the thrust-bearing formed by the upper portion of the transversely disposed flange 24. When the wire has been completely pulled through the driving clip 22, the lifting action of the rotor causes the rotor to move upwardly and to contact the under side of the transverse flange 24 and apply the lifting force thereto. It will be noted that the transversely disposed flange 24 is formed in a somewhat conical surface, and that this surface cooperates with a similarly formed surface on the driving clip. The purpose of this engagement is to create a tendency for the driving clip 22 to be aligned with respect to the axis of the central column.

Disposed immediately below the transverse flange 24, the journal section 26 is provided for cooperation with the central aperture 27 of the rotor. It will be noted that the bearing portion formed by this central aperture 27 is axially short, and that the journal section 26 has considerable length. These characteristics, coupled with the clearance provided between the internal diameter of the aperture 27 and the outside diameter of the journal section 26, permit a considerable angle of tilt to take place between the axis of rotation of the rotor and the axis of the supporting column. This condition is illustrated in Figure 4 of the drawings. Figure 3 of the drawings illustrates the position of these components with the toy in a flight position in which the rotor is contributing no lateral components. This situation is associated with the condition known as "hovering."

The driving clip 22 is preferably provided with engaging legs 23 which are sufficiently yieldable to engage the central portion 25 of the rotor and to retain the same due to the said yielding action. To facilitate the assembly of the device, the engaging legs are provided preferably with the starting surfaces 28 which are the first to contact the central portion of the rotor as the clip is forced into engagement with the same. The slant relationship of these starting surfaces 28 causes the yielding of the legs sufficiently to permit the same to snap into engagement with the rotor into the position shown. The disassembly of the device shown in Figure 1 is accomplished by first removing the twisted wire and spool from cooperating relationship with the toy, then removing the column from the column-engaging elements 13 and 14, removing the driving clip from engagement with the rotor, and then sliding the rotor downwardly with respect to the column until removed therefrom. As thus disassembled, the device is easily packaged and is capable of being reassembled by an unskilled user who can follow a very simple set of directions.

It will be noted that the preferred form of the

journal section 26 shown in the drawings is provided with a downwardly-decreasing taper. The upper end of the journal is adapted for good running clearance when the axis of the rotor is the same as the axis of the journal. When the tilted relationship develops as shown in Figure 4, the taper of the journal gives more freedom than would a cylindrical surface having parallel elements.

The particular embodiments of the present invention which have been illustrated in the accompanying drawings and described herein are for illustrative purposes only. The definition of the present invention is set forth in the claim appended hereto in which it is the intent of the inventor to claim the entire scope of the invention to which he is entitled in view of the prior art.

I claim:

A helicopter toy, comprising: a tubular column having a flange forming a thrust bearing at the normally uppermost end thereof and a tapered journal section having a downwardly-decreasing diameter disposed coaxially with and immediately below said thrust bearing; a lifting rotor

10
15

having a shallow hub provided with a circular central aperture forming a bearing of a size adapted to rotatably engage the largest portion of said journal section and bear against the under surface of said flange; and driving means for said rotor including a downwardly dished transverse plate adapted to bear against the upper surface of said flange having a non-circular central aperture for engaging a matching twisted wire driver and disposed on the opposite side of said flange from said hub in axially spaced relationship establishing substantial clearance between said flange and said hub and plate, said plate being detachably secured to and spaced from said hub by integral leg means extending radially from said plate, outwardly around said flange, and down to and attached to said hub.
